UNITED STATES PATENT OFFICE

2,490,383

CUFF BUTTON FOR SEWED-ON BUTTON
TYPE OF CUFFRogers T. Stafford, East Providence, R. I., as-
signor to B. A. Ballou & Co. Incorporated, a
corporation of Rhode Island

Application December 10, 1947, Serial No. 790,772

3 Claims. (Cl. 24—104)

1

This invention relates to a cuff button.

The cuffs on men's shirts have been formed in two different types. In one type, the button is sewed onto one part of the cuff and a buttonhole is on the other part of the cuff through which the button may pass to secure the edges of the cuff in overlapped relation. Another type of cuff which is formed on men's shirts is designated as the French type cuff in which the opposite edges of the cuff are brought together so that their edges are in registry, and in both parts of the cuff there is provided a buttonhole for the reception of some sort of a button which may be button into each of the buttonholes to hold the cuff in closed relation.

One of the objects of this invention is to provide a device which may be utilized for converting the sewed-on button type of cuff to the French type cuff.

Another object of this invention is to provide a more ornamental securing device for holding a cuff in position than is provided by the pearl button which is usually sewed to one part of the cuff.

Another object of the invention is to provide a metal connection which may be highly ornamented, which will conceal the pearl button, and also will provide a French type cuff with highly ornamental buttons showing on either side of the cuff when in an exposed position.

Another object of the invention is to provide a device which may be easily attached and detached from the pearl button which is sewed to the cuff.

Another object of the invention is to provide a device which may be attached to the pearl button without in any way changing the arrangement of the pearl button on the cuff and which may be readily removed so that the cuff may be restored to its former relation if desired.

With these and other objects in view, the invention consists of certain novel features of construction as will be more fully described and particularly pointed out in the appended claims.

In the accompanying drawings:

Figure 1 is a perspective view of a fragmental portion of a cuff of a man's shirt illustrating the device which I have provided as being positioned thereon;

Figure 2 is a sectional view on substantially line 2—2 of Figure 1;

2

Figure 3 is a perspective view of a part of the device with the ornament which may be attached to one of the arms of this device omitted; and Figure 4 is a section on line 4—4 of Figure 3.

In proceeding with this invention, I provide a strip of stock which I fold to provide a pair of arms, and on one of these arms there is secured a means to attach the arm to a button of the cuff. Some ornament to cover the button is also provided. The other arm is provided with a button which may be passed through the buttonhole of the portion of the cuff which ordinarily receives the pearl button and which itself will serve to attach the two parts of the cuff together with each of the edges in registry, so that a French type cuff may be provided.

With reference to the drawings, particularly Figure 3, 10 designates a sheet metal member which is folded as at 11 to provide an arm 12 and a second arm 13 extending from the fold. The arm 13 is folded as at 14 to provide a pair of fingers 15 which are disposed in a substantially parallel relation to the arm 13 and are distant from the arm 13 a sufficient amount so as to provide a space to receive a button 16 which is sewed to one portion of the cuff 17 by means of sewing as shown at 18. These arms 15 are spaced so that the sewing 18 may be passed into the opening 19 between them and the arms will in some cases be flexed apart slightly so that the sewing will be held tightly between them. An ornament 20 may be secured to the enlarged portion 21 of the arm 13 which will correspond to the button on the other arm to be described. This provides a cover to conceal the pearl button, while the fold 11 extends about the edge 22 of the cuff portion 17 to position the arm 12 on the other side thereof.

This cuff is designated generally 23 and has another portion 24 which is bent from the general circular arrangement of the cuff and which portion is provided with a buttonhole 25.

The arm 12 is provided with a button 26 as shown in Figure 2 or in Figure 3 which is so shaped that it has a head 27 with an undercut portion 28 and an inner head 29. This button 26 may be passed through the buttonhole 25 in cuff portion 24 so as to secure the portions 17 and 24 of the cuff together with their edges in sub-

stantial registry as is done in the French type of cuff.

By this arrangement the pearl button and buttonhole securing arrangement of the cuff may be transferred to the French type of cuff which is more ornamental and which receives a highly ornamental metal cuff link to secure the parts together so that a much more dressy shirt is thus provided.

I claim:

1. A device for converting a cuff of the overlapping button and buttonhole type to a French type cuff comprising a member having a pair of integral arms to extend generally in the same direction and in spaced relation from a point of junction at the edge of the portion of the cuff carrying the button inwardly therefrom at an acute angle on opposite sides thereof, means on the arm on the button side of said cuff to secure it to the button on the cuff and a button on the other arm to pass through the buttonhole of

15

the cuff to attach the two cuff portions together and form a French type cuff.

2. A device as in claim 1 wherein the means to attach to the button of a cuff comprises a pair of fingers carried by the arm to extend beneath the button.

3. A device as in claim 1 wherein the means to attach to the button of a cuff comprises a pair of fingers folded from the stock of the arm to a position spaced therefrom for extending beneath the button of a cuff.
